CLAIM

We claim the ornamental design for a pipe coupling, as shown and described.

DESCRIPTION

FIG. 1 is an isometric view of our design for a pipe coupling; FIG. 2 is a front view of the design of the pipe coupling shown in FIG. 1, the rear view being a mirror image thereof; FIG. 3 is a left side view of the design of the pipe coupling shown in FIG. 1, the right side view being a mirror image thereof;

FIG. 4 is a top view of the design of the pipe coupling shown in FIG. 1; and,

FIG. 5 is a bottom view of the design of the pipe coupling shown in FIG. 1.

The broken lines depict portions of the pipe coupling that form no part of the claimed design.
